CLAIM

The ornamental design for a bottle, as shown and described.

DESCRIPTION

FIG. 1 is a perspective view of a bottle showing our new design;

FIG. 2 is a front view of the bottle depicted in FIG. 1; FIG. 3 is a right side elevation of FIG. 2, the rear and left side elevations are the same except for the conventional screw threading on the bottle neck and the placement of the indentations on the base;

FIG. 4 is a top view of the bottle depicted in FIG. 2;

FIG. 5 is a bottom view of the bottle depicted FIG. 2;

FIG. 6 is a perspective view of a second embodiment of a bottle as depicted in FIG. 1;

FIG. 7 is a front view of the bottle depicted in FIG. 6;

FIG. 8 is a right side elevation of FIG. 7, the rear and left side elevations are the same except for the conventional screw threading on the bottle neck and the placement of the indentations on the base; and,

FIG. 9 is a top view of the bottle depicted in FIG. 7.

The bottom of the second embodiment is the same as the bottom of the first embodiment.
